S. ELLIS.

WATER HEATER.

APPLICATION FILED NOV. 23, 1912.

1,076,274.

Patented Oct. 21, 1913.

UNITED STATES PATENT OFFICE.

STUART ELLIS, OF WASHINGTON, DISTRICT OF COLUMBIA.

WATER-HEATER.

1,076,274.

Specification of Letters Patent.

Patented Oct. 21, 1913.

Application filed November 23, 1912. Serial No. 733,105.

To all whom it may concern:

Be it known that I, STUART ELLIS, a citizen of the United States, residing at Washington, in the District of Columbia, have invented new and useful Improvements in Water-Heaters, of which the following is a specification.

This invention is, more particularly, an improvement upon the water-heating devices shown and described in United States Patents Nos. 864,760 and 1,026,013.

The object is to provide means to direct the hot products of combustion into contact with the water-pipe to be heated, and, to this end, the invention contemplates the provision of peculiar guide-plates, for the purpose specified.

Another object is to provide a valve operable, when the hot water is being withdrawn from the boiler (or other liquid-containing tank) in connection with which my heating-apparatus is used, to automatically control the inlet of cold water to the boiler, through the water-heater, whereby the volume or flow of cold water passing to the boiler is appreciably diminished or decreased, so that the hot water in the boiler may not be unduly or undesirably chilled.

To this end, the invention consists in the provision of a peculiar form of valve, normally seated at the bottom of the water-pipe to be heated, and in the region of the burner; said valve subserving the additional function of causing the cold water entering the water-pipe to be spread out in a thin sheet, so as to be more quickly heated by the burner.

Subsidiary objects of improvement will appear as the specification proceeds and the nature of the invention more fully appears.

In the accompanying drawings, forming part of the specification, and in which like numerals of reference indicate corresponding parts throughout the several views: Figure I is a perspective view of my heating apparatus; Fig. II is a central, vertical section thereof, on an enlarged scale; Fig. III is a perspective detail view of my peculiar valve.

Referring, now, in detail to the drawings: 1 represents or designates a casing or drum, which may be suitably secured, at the lower end thereof, to a skeleton or spiderlike base 2, and closed at the top in any suitable manner, as by a cap 3. Internally of the drum, and preferably concentric therewith, is a

tube 4, screw-threaded at both ends, as shown. On the top and bottom of said tube 4 are screwed, respectively, caps 5 and 6, having threaded apertures therethrough, 7, 8, for connection with pipes leading, respectively, to the upper and lower ends of a boiler (not shown), or the like.

Inside the drum 1 and seated upon the skeleton base 2 is a burner, designated, generally, by 9, of peculiar construction, with which communicates, in a peculiar manner, an air-mixer or carbureter 10, also of peculiar construction. The shape of the burner is, as shown, preferably annular in horizontal cross section; and the burner is provided, internally, with a concentric, vertical diaphragm or wall 10', between which and the outer wall of the burner is a chamber 11, annular in horizontal cross section. The diaphragm 10' is provided with a symmetrically disposed series of vertical slots 12, which are parallel with and in juxtaposition to the tube 4, so that the hot products of combustion from the burner 9 are shot and impinge directly against the tube 4, insuring a rapid heating thereof and of the water passing therethrough. As shown, the slots 12 extend, by preference, from the top to the bottom of the diaphragm 10'. The burner may be held in proper position, with respect to the tube 4, in any suitable manner, preferably by vertical ribs 13 carried by the diaphragm 10'.

In order readily to ignite the gas passing through the slots 12, the drum 1 is provided with a door 18, which, by preference, extends the entire length thereof, and is conveniently hinged at one end, as at 19, to the drum, and maintained in normal closed position by a latch 20.

Internally of the tube 4, and normally resting against the bottom of the cap 6, is a valve 21, which is, desirably, a hollow cylinder, closed at the top, as at 22, said top being provided with a vent 23. The valve terminates, at the bottom, in depending, spaced feet 24, which rest normally against the bottom of the cap 6. The valve 21 is of slightly less diameter than the tube 4, so that it fits loosely therein, and is thus capable of vertical reciprocation therein. One of the purposes in constructing the valve as a cylinder is to compel the water entering through the opening 8 to flow between the feet 24 and between the valve 21 and the tube 4 in a thin sheet, so that the

water is readily and quickly heated by the burner. Normally, as stated, the valve occupies a position at the bottom of the tube 4; but, when water is being withdrawn from the boiler, the pressure and considerable volume of water through the inlet 8 will lift the valve from its seat on the cap 6 and raise it until it bears against the cap 5 at the top of the tube 4, thereby cutting off escape of water from the tube 4, except through the small vent 23 in the valve. The valve is shown in such raised position in Fig. 2. This will prevent a great excess of cold water entering the boiler, while the warm water therefrom is being withdrawn, and, by this means, appreciable chilling of the water in the boiler is obviated. When the operation of drawing off a quantity of warm water from the boiler ceases, the valve 22 drops back, by gravity, to its normal position upon the cap 6. It will thus be seen that the member 22 subserves a dual function,—1, that of a valve, and, 2, that of spreading out the water in a thin sheet, so as to be quickly heated.

Interiorly of the drum 1 and at a point somewhere above the burner 9, I provide a deflecting-member, which, in this instance, takes the form of a truncated cone, formed, desirably, in two segmental sections or halves, one section 25 being secured to, or formed integral with, the door 18, and the other section 26 being secured to the drum 1, and the two sections constituting lips. The top rim 27 of the lips is somewhat removed from the tube 4, so that there is an escape of the hot products of combustion between this rim and the tube 4. The function of these lips 25, 26, as is obvious, is to guide or direct the hot products of combustion in the direction of the tube 4, so as to strike thereagainst before they pass through the lips 25, 26.

Near the top 3 of the drum 1, I desirably provide a horizontal plate or shelf 27, which projects into the drum 1 from one side thereof and extends to and terminates at the tube 4 (as shown in Fig. 2). The function of this plate 27 is to obstruct the passage of the hot gases, and cause them to flow into contact with the tube 4, before they escape through the exit 28 provided at the top of the drum 1, above the plate 27.

While I have described, with great particularity, a particular embodiment of my invention susceptible of carrying out the underlying principles thereof, I am aware that many changes and modifications may be made; but all such changes and modifications as fall within the terms of the ap-

pended claims constitute no departure from the spirit of the invention.

Having thus fully described my invention, what I claim as new and desire to secure by Letters-Patent of the United States is:

1. In a heating apparatus, the combination with a water-tube provided with an inlet end and an exit end, of a reciprocable cylindrical member fitting loosely within said tube, whereby water entering the latter is spread out in a thin stream between said tube and member and thereby quickly heated, said member being provided with a vented top and being normally seated, at the opposite end thereof, at the inlet end of said tube, and heating means for said tube disposed in the region of said inlet-end thereof. 75

2. In a heating apparatus, the combination with a water-tube provided with an inlet end and an exit end, of a reciprocable cylindrical member loosely fitting within said tube, whereby water entering the latter is spread out in a thin stream between said tube and member and thereby quickly heated, said member being provided with a 80 vented top and being provided, at the other end thereof, with spaced feet, and said member being normally seated at the inlet-end of said tube, and heating means for said tube disposed in the region of said inlet-end thereof. 90

3. In a heating apparatus, the combination with a water-tube, of heating means for said tube disposed toward the lower end thereof, a drum inclosing said water-tube, a 95 door hinged to said drum, and a two-section truncated cone-shaped member disposed in said drum above said heating-means one of said sections being carried by said door and the other of said sections by said drum. 100

4. In a heating apparatus, the combination with a water-tube, of heating means for said tube disposed toward the lower end thereof, a drum inclosing said water-tube, a door hinged to said drum, a two-section 105 truncated cone-shaped member disposed in said drum above said heating means, one of said sections being carried by said door and the other of said sections by said drum, and a partition disposed above said cone-shaped 110 member and projecting into said drum from one side thereof and extending to and terminating at said water-tube.

In testimony whereof, I have hereunto set my hand in presence of two subscribing witnesses.

STUART ELLIS.
